UNITED STATES PATENT OFFICE.

JAMES G. WINSOR, OF DETROIT, MICHIGAN.

STABILIZER FOR DUMPING-VEHICLES.

1,245,651.

Specification of Letters Patent.

Patented Nov. 6, 1917.

Application filed April 23, 1917. Serial No. 163,767.

To all whom it may concern:

Be it known that I, JAMES G. WINSOR, a citizen of the United States, residing at Detroit, county of Wayne, State of Michigan, have invented a certain new and useful Improvement in Stabilizers for Dumping-Vehicles, and declare the following to be a full, clear, and exact description of the same, such as will enable others skilled in the art 10 to which it pertains to make and use the same, reference being had to the accompanying drawings, which form a part of this specification.

This invention relates to stabilizers for 15 dumping vehicles. It comprises one or more devices which are arranged to hold the self-dumping hopper in its carrying position, and which are adapted to allow the chassis to turn with respect to the hopper 20 on its major axis without carrying the heavy hopper with it. The device may also serve to start the hopper in dumping when the same is released on one side.

These features will be more minutely explained in the specification following.

In the drawings,—

Figure 1 is the end view of the vehicle chassis carrying the dumping hopper.

Fig. 2 is an elevation of the stabilizer.

Fig. 3 similarly is an elevation of the stabilizer but taken from a 90 degree point.

Fig. 4 is an elevation of a modified form of stabilizer.

The vehicle chassis is designated *a*, the 35 hopper *b*. This hopper is mounted to roll upon the cross rails *c* of the chassis by means of the circular rockers *d* which pass under the V-like hopper and rise comparatively high on the sides for the purpose of bringing the center of the rockers only slightly below the center of gravity of the load when the hopper is filled. This accomplishes a very useful function in that the load is only slightly over-balanced and consequently 40 when the hopper is released on one side the load will roll easily and not precipitately to the dumping position. It is also advisable to have the center of the rockers high as this insures more metal in the hopper 45 per below the center of the rocker than above and consequently when the load is discharged the hopper will automatically return to its central position.

The stabilizers are shown on each side in 50 Fig. 1, and comprise linear members connecting the top of the hopper with the chassis.

sis (specifically, the rails *c*) and which are yieldingly extensible and contractible and which are capable of being shortened and lengthened by means of a device having a 60 mechanical advantage. A portion of the linear member is a chain *e*. The portion which makes the same yieldingly extensible or contractible comprises a pair of yokes *f*, *g*, each of which has at the end an abutment plate *h* and each of which slides through the abutment plate of the other yoke. Between these abutment plates engages the strong coiled spring *i*. By reason of the arrangement of the two yokes and the abutment plates, this spring makes the 70 linear member yieldingly extensible.

The device which serves to make possible the shortening of the linear member with the aid of mechanical advantage comprises 75 a bent lever *j* which has a fulcrum in the yoke *l* at the point *k* and which has its power arm connected with one yoke *g* by means of the link *m*. On the lower end of this shortening device a hook *n* is provided 80 which may be hooked into the uppermost link of the chain part *e*. Now, when this linear member is in the position indicated by dotted lines of Fig. 2, obviously it has its greatest length and in that position the 85 hook *n* may be released from the chain part *e*. When the parts of the linear member are in the position shown in Fig. 2, full lines, the linear member is shortened and all the parts firmly held together.

In Fig. 4, instead of a bent lever device for shortening the linear member a hook-like lever *p* is shown. When this is drawn up to a position of substantial parallelism with the linear member as shown in Fig. 4, the 95 lever by reason of the peculiar shaping of the gullet of the hook shortens the linear member. The lever may be held in this position of parallelism by hooking the end of it within a clip attached to the chain.

Now, obviously, from the above description, the chassis of the vehicle may rock under the hopper. The rocking of the chassis is made possible by reason of the yieldable ties between the chassis and the 105 top of the hopper. This is really the action that will occur when the vehicle is traveling along a rough road, as the chassis will tend to follow the action of the wheels except in so far as the vehicle springs make 110 this unnecessary, while on the other hand the loaded hopper has a great amount of in-

ertia because of its great relative weight. Consequently a great part of the unevenness of the road is not communicated to the loaded hopper by reason of these spring stabilizer devices and the rolling mounting of the hopper upon the chassis. This avoids a great many heavy twisting strains on the hopper and the chassis.

We have already described this hopper as a substantially self-dumping device. If the center of gravity of the load is above the center of the rockers and slightly to one side, the hopper would dump itself, but as roads are seldom absolutely level and as the loads are not very frequently evened off on top to accomplish precisely this result, the spring in the linear member at one side, when the linear member at the other side is released, serves to overcome any slight displacement of the center of gravity from the proper position of automatic operation.

What I claim is:

1. In a dumping vehicle, the combination of a chassis, a hopper pivotally mounted thereon, and yieldably extensible stabilizers extending from the side of the hopper to the chassis.
2. In a dumping vehicle, the combination of a chassis, a hopper that dumps to either side, and yieldably extensible stabilizers extending from both sides of the hopper to the chassis.
3. The combination as claimed in claim 2 with stabilizers comprising linear members which are yieldingly extensible and which are put under tension when tightened, the hopper being near balance in its central po-

sition so as to easily be tipped to one side or the other.

4. The combination as claimed in claim 2, with stabilizers comprising linear members yieldingly extensible and which are also capable of being shortened to put them under tension, the said hopper being near balance in its central position so as to be easily tipped to one side or the other.

5. A combination of devices claimed in claim 4, with stabilizers comprising linear members which may be shortened by the aid of a device having mechanical advantage.

6. The combination claimed in claim 4, provided with stabilizers comprising each a pair of yokes having at their forked ends abutment plates, and each yoke guided through the abutment plate of the other yoke, and a coiled spring engaging between the abutment plates.

7. The combination claimed in claim 6, provided with stabilizers having devices for shortening the linear members comprising bent levers, substantially as described.

8. In a dumping vehicle, the combination of a chassis, a hopper that dumps to either side, and stabilizers extending from both sides of the hopper to the chassis and comprising chains, a portion of each of which is made up of a spring which may be contracted, and a lever for putting the spring under tension by shortening the length of the entire stabilizers.

In testimony whereof, I sign this specification.

JAMES G. WINSOR.
